(57) **CLAIM**

The ornamental design for a spray cap for aerosol cans or similar fluid containers, as shown and described.

DESCRIPTION

FIG. 1 is a perspective front view of the spray cap for aerosol cans or similar fluid containers showing the new design;

FIG. 2 is a perspective rear view of the design shown in FIG. 1;

FIG. 3 is a right elevational front view of the design shown in FIG. 1;

FIG. 4 is a left elevational front view of the design shown in FIG. 1;

FIG. 5 is a right elevational rear view of the design shown in FIG. 1;

FIG. 6 is a left elevational rear view of the design shown in FIG. 1; and,

FIG. 7 is a top plan view of the design shown in FIG. 1.

The dashed lines showing the spray container are for illustrative purposes only and form no part of the claimed design.

1 Claim, 7 Drawing Sheets
